UNITED STATES PATENT OFFICE.

CHARLES H. VOUTÉ, OF PHILADELPHIA, PENNSYLVANIA.

IMPROVEMENT IN APPARATUS FOR CLEANING PRIVY-VAULTS.

Specification forming part of Letters Patent No. 178,213, dated May 30, 1876; application filed May 4, 1876.

To all whom it may concern:

Be it known that I, CHARLES H. VOUTÉ, of Philadelphia, in the county of Philadelphia and State of Pennsylvania, have invented a new and valuable Improvement in Apparatus for Cleaning Privy-Vaults; and I do hereby declare that the following is a full, clear, and exact description of the construction and operation of the same, reference being had to the annexed drawings, making a part of this specification, and to the letters and figures of reference marked thereon.

Figure 1. of the drawings is a representation of a side elevation of my machine as in use, and Figs. 2, 3, and 4 are sectional detail views of my barrel and valves. Fig. 5 is a vertical central sectional view of my barrel.

My object is to improve processes for cleaning privy-vaults; and the nature of my invention consists in a novel process of removing matter from privy-vaults without allowing the escape of fetid odors; said process consisting in the employment of an air-pump of the double-acting kind, in combination with detachable air-pipes and a receiver, which has the main conducting-pipes attached to it, as will be hereinafter explained.

Prior to my invention it was necessary to detach the main pipes from the receivers during the operation of removing matter from privy-vaults. This allowed an escape of fetid odors, and was the cause of much delay. I am able by my improved process to empty a vault without detaching the main pipes; and I also avoid the labor of moving filled barrels from the privy-vaults to the transporting-wagon in the street.

In the annexed drawings, A designates a receiving-tank, which is mounted on wheels and designed for the transportation of the matter pumped out of the privy-vaults. B designates a portable receiver, which communicates with the tank A by a hose, C, and also with the privy-vault D by a hose, E. F designates a double-acting air-pump, which is mounted on wheels for convenience of moving it, and which communicates with the receiver B by means of an air-pipe, a; and G designates a deodorizer, which communicates with the cylinder of the pump by means of an air-pipe, b. The large main pipes or hose C E

are connected to the head of the receiver B by means of coupling-boxes g g', which are provided with valves h h', and which can be readily detached from the receiver when not in use.

When these coupling-boxes are detached from the head of the receiver closely-fitting caps are applied in their places. The air-pipe a should be provided with a valve on that end which is connected to the receiver B, which valve has attached to it a float that will rise and shut the valve when the receiver is full.

The operation with a single receiver is as follows: Pipes C E are arranged as shown in Fig. 1. Pipe a is connected to the receiver B and to the exhaust end of the pump-cylinder. The pipe b is connected to the forcing-end of the pump-cylinder and to the deodorizer G. All of the pipes are detachable. Under the arrangement shown in Fig. 1, when the pump F is operated, it will exhaust from the receiver B, and cause the matter from the vault D to fill this receiver, the valve h being open and the valve h' being shut.

When the receiver B is filled the valve h is shut and valve h' is opened. The interchangeable pipes a and b are detached, respectively, from the pump F and deodorizer G, and the free ends a' and b' of the pipes are connected together by means of male and female couplings, thereby forming a continuous hose or pipe from the force part of the pump F to the receiver B, as indicated by dotted lines. Then the pump is started again, which pumps air into the upper portion of the receiver, and forces the matter out of the same through pipe C into the transporting-tank A. The valve h' is then shut, and the valve h opened, after which the pump F is started, and the receiver B again filled, previous to which the air-pipes are adjusted, as shown in Fig. 1, so that during the act of exhausting air from the receiver B, and filling the same, the fetid air will be forced through the deodorizer G.

To make the process continuous, I use two receivers, B B, communicating with each other and with the privy-vault, and also with the transporting-tank; and to each receiver an air-pipe is attached, which pipes communicate, respectively, with the exhausting and forcing ends of the pump-cylinder. By changing the

connections of these pipes the barrels or receivers can be filled and emptied alternately—that is to say, while one receiver is being filled the other will be emptied of its contents, and vice versa.

It will be observed that during the process of transferring the matter from the privy-vault to the transporting-tank, the only thing necessary is to keep the air-pipes properly adjusted. The main conveying-pipes are not changed after they are once fixed.

The receiving-tank B forms an integral part of the apparatus used for forcing the matter from the privy-vault into the transporting-tank, and is practically a part of the air forcing and exhausting engine, representing the

air-chamber thereof. Of course, suitable deodorizers will be attached to the transporting-wagon.

What I claim as new, and desire to secure by Letters Patent, is—

In the process of emptying privy-vaults, the conveying pipes or hose C E, a receiver, B, a double-acting air-pump, and interchangeable pipes *a b*, substantially as described.

In testimony that I claim the above I have hereunto subscribed my name in the presence of two witnesses.

CHARLES H. VOUTÉ.
